Fig. 3.

A technical line drawing of a standard three-prong electrical plug. The plug is oriented vertically. The top contact is labeled 10. The left contact is labeled 15. The right contact is labeled 14. The ground connection at the bottom is labeled 11. Callouts with numbers 7 through 20 point to various parts of the plug, including the top contact, the left contact, the right contact, the ground connection, and the overall structure of the plug.

ELECTRICAL PLUG AND RECEPTACLE

John F. Navert, Alfred Max Steinmetz, and Alfred Ernest Steinmetz, Jr., Philadelphia, Pa.

Application April 9, 1934, Serial No. 719,766

1 Claim. (Cl. 173—330)

This invention appertains to new and useful improvements in electrical connectors, and more particularly to a novel electrical plug and receptacle therefor.

5 The principal object of the present invention is to provide a novel plug and receptacle therefor wherein the plug and receptacle are constructed in such a manner as to permit a slight movement of the plug after insertion to cause 10 the plug to be fastened securely to the receptacle with its contact prongs in electrical connection with the contacts of the receptacle.

Another important object of the present invention is to provide a novel plug and receptacle 15 of extreme simplicity, to the end that the same can be manufactured at a cost not exceeding the cost of manufacturing present day type of wall receptacles and plugs, of the prong type.

Still another important object of the present 20 invention is to provide an electrical plug and receptacle wherein the plug is constructed in such a manner as to permit insertion and fastening of the plug to the receptacle, a simple and quick operation, and wherein its construction is substantially fool-proof.

Other important objects and advantages of the invention will become apparent to the reader of the following specification.

In the drawings:—

30 Figure 1 represents a front elevational view of the receptacle, with one of the plugs engaged therewith.

Figure 2 represents a front elevational view of the receptacle removed from its mounting.

35 Figure 3 represents a front elevational view of the box portion of the receptacle, with the springs installed therein.

Figure 4 represents a front elevational view of the receptacle box, with the springs removed.

40 Figure 5 represents a vertical sectional view taken substantially on line 5—5 of Figure 1, showing the receptacle in side elevation, with parts broken away.

Figure 6 represents a longitudinal sectional view through the receptacle.

45 Figure 7 represents a cross sectional view taken substantially on line 7—7 of Figure 4.

Figure 8 represents a plan view of one of the spring members.

50 Figure 9 represents a side elevational view of the plug.

Figure 10 represents a front elevational view of the plug.

55 Figure 11 represents a side elevational view of a fuse type of plug.

Figure 12 represents a front elevational view of the fuse type of plug.

Referring to the drawings wherein like numerals designate like parts, it can be seen in Figure 5 that numeral 5 represents the wall of a building provided with the pocket 6 therein for receiving the novel receptacle construction 7. The receptacle structure disclosed in the drawings is of the dual socket type and consists of the box-like structure 8 provided with the cross member 9 therein and the dividing members 10—10 extending inwardly from the opposite ends thereof. The cross member 9 is provided with openings 11 in the ends thereof into which the screws 12 can be engaged for clamping the intermediate portions of the elongated spring strips 13 to the cross member 9, the cross member 9 being cut away at the points 14—14 to provide seats for the spring strips 13. Inwardly extending members 10—10 also have openings 15 therein for receiving the screws 16 which extend through the cap member 17.

This cap member 17 is provided with a pair of head-like formations *a—a* connected by a reduced neck portion *b* and each of the head portions *a—a* is provided with a pair of arcuate-shaped slots 18—18, each opening at one end into an enlarged circular opening 19. A free end of each of the springs 13 is disposed under a corresponding slot 18.

30 Numeral 20 represents the usual strap which is disposed along the back side of the box 8 with its ends bent outwardly and apertured to receive the retaining screws 21. Numeral 22 represents a cover plate which is secured by a screw 23 to the cap member 17 of the receptacle.

The novel plug structure is generally referred to by numeral 24 and consists of the knob-like body 25 having a pocket 26 in the forward side thereof. A conductor opening 27 extends through the body 25. To the bottom of this pocket 26 are secured the base members 28—28 of the plug prongs 29—29, each provided at its outer end with a ball-shaped head 30.

In the use of the plug, the ball-shaped heads 30 are inserted through the circular openings 19 of the cap member 17 and pushed against the springs 13—13, while at the same time the plug is rotated slightly so that the prongs 29 are brought into the slots 18. As the diameter of the heads 30 exceeds the width of the slots, the heads will simply bear against the under side of the cap plate 17 and be retained in this position by the tension of the corresponding contact springs 13.

In Figures 11 and 12, a modification of the invention is shown wherein the same principle is adapted to a fuse plug. Numeral 31 designates the fuse body which is provided with a window 32 at one end and a pocket 33 at its other end. The bases 34 of a pair of prongs 35-36 are secured to the bottom of this pocket 33, while on each of the bases 34 is a spring clip 36. These spring clips serve to engage the contact heads 37 of a fuse glass 38 through which the fuse wire 39 extends. The prongs 35 are also provided with ball-like heads 41 and the fuse receptacles can be constructed in the same manner as the wall receptacles hereinbefore described. Obviously, a fuse plug constructed in this manner can be retained over a considerable period of time, its use necessitating only the replacement of the fuse cartridge from time to time, as required.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:—

A duplex electrical outlet receptacle comprising an elongated block of insulation provided with an elongated pocket therein, a transverse member in the block dividing the block into a pair of compartments, said cross member protruding at its ends beyond the sides of the block and provided with screw openings in the protruding portions thereof, a pair of elongated spring contactors each provided with a lateral formation at its intermediate portion apertured for disposition over the corresponding screw opening of the cross member, a screw for each of the lateral formations disposed through the opening 15 therein and into the opening of the cross member end, a cover for the block having a reduced intermediate portion to avoid the aforementioned screws, said cover being provided with plug prongs-receiving openings opposed to corresponding ends of the said spring contactors.
